UNITED STATES PATENT OFFICE.

ALFRED DUCASBLE, OF PARIS, FRANCE.

DESIGN FOR A TIRE.

SPECIFICATION forming part of Design No. 33,302, dated October 2, 1900.

Application filed January 15, 1900. Serial No. 1,562. Term of patent 14 years.

To all whom it may concern:

Be it known that I, ALFRED DUCASBLE, a citizen of the Republic of France, residing at Paris, France, have invented and produced a new and original Design for a Tire, of which the following is a specification, reference being had to the accompanying drawings, forming part hereof, in which—

Figure 1 is a perspective view of a tire having my design. Fig. 2 is a cross-section hereof.

The leading feature of the design comprises the tire illustrated in the drawings, and which is characterized by a perfectly-flat tread and by substantially curved sides, which form sharp edges at their union with the tread and have sharp corners at their bases.

In the drawings, *a* is the tread, and *b* represents curved sides provided with ribs or projections *c*. The corners *d* at the unions of the tread and sides are sharp, as are also the corners *e* at the bases of the sides.

Having thus described my invention, what I claim as new, and desire to secure by Letters Patent, is—

The design for a tire, substantially as shown and described.

In testimony whereof I have hereunto signed my name.

ALFRED DUCASBLE.
